Carlos P. Griffin
ATTORNEY.

UNITED STATES PATENT OFFICE.

EDWIN CLINTON SHARPE, OF PIEDMONT, CALIFORNIA.

COAL-BUNKER SYSTEM.

Application filed June 25, 1923. Serial No. 647,532.

To all whom it may concern:

Be it known that I, EDWIN CLINTON SHARPE, a citizen of the United States, residing at Piedmont, in the county of Alameda, State of California, have invented a new and useful Coal-Bunker System, of which the following is a specification, in such full and clear terms as will enable those skilled in the art to construct and use 10 the same.

This invention relates to a coal bunker system in which the coal is discharged from a car in such a manner as to involve the minimum movement of the coal along the 15 bunker system. It will be understood by those skilled in the art that in handling coal in a retail yard, that the coal is either sacked for shipment or delivery, or is run into a truck for delivery, and it must be 20 of a given grade as to size to be acceptable to the customer.

Ordinarily the bulk of the coal purchased will be of the desired size so this bunker is arranged to receive and detain the largest 25 portion thereof where dumped, the oversize being delivered to breakers and the undersize, which is the smallest part, is then delivered to other separators and bins of the system where in turn the finest material 30 only is carried along to be again separated.

This process may be repeated as often as necessary to give the desired number of sizes until at the end a rotary screen may be 35 used to separate and deliver the finest materials into three sizes, to-wit: the dust, pea and small nut, which are then about equal in percentages.

Other objects of the invention will appear as the description proceeds.

An embodiment of the invention is shown 40 in the accompanying drawings in which the same reference numeral is applied to the same portion throughout, but I am aware that there may be modifications thereof.

Fig. 1 is a side elevation of the complete 45 bunker system, only two of the platforms being shown.

Fig. 2 is a vertical sectional view of the 50 first bunker, the plane of section being at right angles to Fig. 1,

Fig. 3 is a side elevation of the first 55 bunker looking in the opposite direction from Fig. 1, showing the location of the breaker,

Fig. 4 is a plan view of the bunkers, the

relative sizes being indicated roughly by the areas thereof,

Fig. 5 is a sectional view of the second bunker, and

Fig. 6 is a sectional view of the third 60 bunker.

The bunker is built in the usual manner of large coal bins, having heavy supporting posts 1, which are connected by the joists 2 and stringer 3.

There is an incline 4 up which the cars 5 may be delivered to the platform 6.

In front of some or all the chutes 7, there may be a sacking platform 8 at a convenient elevation to allow the workmen to fill the 70 sacks directly from the chutes 7.

Within the bunker there is a baffle board 9 to prevent the coal from passing directly into the chutes 10 to 12 inclusive, at the bottom of the 6-inch grizzly bars 13 on which 75 the coal is dumped. The coal passing through the 6-inch grizzly bars falls on a screen 14 having 6-inch square or round openings so the material passing through it will be the smaller materials passing the 80 6-inch grizzly.

The material retained on the screen 14 is ready to be delivered either to sacks or wagons from the chutes 7, suitable gates 7' being provided in said chutes to prevent 85 the coal from running out on the platform, except when it is desired to allow it to escape.

Extending under the full length of the 6-inch bunker is a conveyor 15 which receives the coal passing through the screen 14, hopper floors 16 and 17 directing it onto the said conveyor. The conveyor 15 discharges its materials in a hopper 18 from which the endless elevator 28 takes it to 90 the top of the next bunker of the system.

At the bottom of the chutes 10 to 12 there is a suitable large breaker, indicated herein, by the two breaker rolls 19 and 20 through which the large lumps are passed to reduce 100 their size. The coal is then dropped into a hopper 21 from which it is taken by the elevator 22 to the top of the bunker again for further separation by the grizzly 13 and screen 14.

The screen 14 is suitably supported to allow the accumulation thereon of an entire bin full of coal, if necessary or convenient.

The elevator 28 discharges the coal delivered to it on a screen 29 in the bunker 30,

110

a slide 31 causing the coal to be dumped near the center of the bin, said bunker being constructed similar to the first bunker, but with the omission of the car platform. 5 The screen 29 is provided with 2½ inch holes, and whatever material passes through it falls on the incline 32, and is delivered to the conveyor 33.

The material elevated by the conveyor 33 10 is dropped on a slide 34 which delivers it to the center of the bunker 35 in which there is a screen 36 having one and one-half inch holes. The material passing this screen 36 falls on the floor 37 and is then delivered to 15 the elevator 38 by which it is dumped into the chute 39 from which the coal passes into the rotary screen.

The screen 40 is arranged to deliver materials which do not pass through it into the 20 bin 41. Outside the screen 40 there is a reversely placed frusto-conical screen 42 arranged to deliver materials which do not pass through it to the bin 43, the dust being dropped into the bin 44. Chutes 45 to 51 25 enable the coal to be drawn from the bins as may be required and they are at an elevation such as will enable trucks to be filled direct or the platforms 8 may be moved under said chutes to enable the workmen to fill sacks 30 easily.

The operation is as follows:

A car of coal is dumped into the first bunker. The bulk of this coal will remain 35 in the bunker ready for delivery. The larger lumps will pass to the breaker and will after being broken be returned to the bin. The finest material will then be taken by the conveyors 15 and 28 to the second bin where all materials under two and one-half 40 inches will be dropped on the chute 32 and will then be taken by the elevator 33 to the top of the bunker 35. This will pass all sizes under 1½ inches and then the finest materials will be delivered to the rotary 45 screens for the final separation.

While the percentages of fine to coarse material will vary with different coals the screens used can be varied in size as may be required to handle any given coal with the 50 minimum amount of transference, thereby greatly economizing on the power used as well as economizing in coal breakage since the less the coal is handled the less coal there is broken.

65 What I claim is as follows, but modifications may be made in carrying out the in-

vention shown in the drawings and in the above particularly described from thereof, within the purview of the invention.

1. A coal bunker system, comprising a 60 bin, a bin having screens to separate the material into three sizes, a breaker to which the coarsest material is passed, said bin retaining the intermediate material, chutes for loading wagons or filling sacks from the 65 intermediate size material retained in said bin, a conveyor to take the broken material from the breaker back to the bin and another conveyor to take the finest material to a place of storage. 70

2. A coal bunker system, comprising a bin having screens to separate the coal into three sizes, said bin retaining the intermediate size materials, chutes extending from said bin to load the intermediate sized materials, a breaker to which the coarsest material is sent, an elevator to return the broken material to the bin, a conveyor to take the finest material to another bin adapted to separate the material into two sizes the 80 finest material passing to a place of storage away from that bin. 85

3. A coal bunker system, comprising a bin having screens to separate the material passed thereto into three sizes the intermediate size remaining in the bin, a breaker to which the coarsest material passes, a conveyor to return the broken material to the bin, another conveyor to carry the finer material to another bin the latter bin having 90 a screen to separate the material into two sizes the finest material passing to a conveyor from which it is elevated to a place of storage. 95

4. A coal bunker system, comprising a bin, screens therein to separate the material into three sizes the intermediate size remaining in the bin, a coal breaker to which the largest size is passed, an elevator to return the broken coal to the bin, a conveyor to take the finer material to a second separating bin the latter bin having a screen to separate the coal into two sizes, a conveyor adapted to take the finest material from the latter bin to another separating bin and another conveyor adapted to take the finest material from that bin to a final place of storage. 105

In testimony whereof I have hereunto set my hand this 15th day of June A. D. 1923.

EDWIN CLINTON SHARPE.
